UNITED STATES PATENT OFFICE.

RUSSELL P. TYLER, OF SAN FRANCISCO, CALIFORNIA.

AUTOMOBILE HEADLIGHT.

Application filed November 1, 1926. Serial No. 145,449.

This invention relates to adjustable headlights of the search or spotlight type and especially to improvements in the mounting and adjusting mechanism employed.

5 The object of the present invention is to generally improve and simplify the construction and operation of a headlight of the character described; to provide a mounting which permits the head-light to be positioned and secured in front of the radiator of an automobile; to provide a mounting which permits the light or beam projected to be moved through a wide range and further to provide an actuating mechanism 10 whereby movement of the beam or light may be readily controlled.

One form which the invention may assume is shown by way of illustration in the accompanying drawings, in which:

20 Figure 1 is a central vertical longitudinal section through the head-light,

Figure 2 is a diagrammatic view showing the range of movement of the projected beam,

25 Figure 3 is a front view of the radiator of an automobile showing the head-light attached thereto,

Figure 4 is a side elevation of Figure 3,

30 Figure 5 shows a modified form of the structure disclosed in Figure 1.

Referring to the drawings in detail and particularly to Figures 3 and 4, A indicates the radiator of an automobile, B the spout and radiator cap and C the head-light forming 35 the subject matter of the present application. The headlight proper is best illustrated in Figures 1 and 3. It consists of a substantially cylindrical-shaped housing 2 provided with a back section 3 and a front window or lens 4 which is attached or secured to the housing in the usual manner. Disposed centrally of the back section 3 is 40 a bearing member 5 and journaled therein is a shaft 6, the function of which will herein-after be described.

Suitably secured on the forward end of the shaft or that portion which extends into the housing is a bracket member or socket 7 and carried thereby is a parabolic reflector 50 8 and a surrounding ornamental or covering

plate 9, the plate 9 being formed integral with the reflector 8, as here illustrated or being suitably secured thereto, if desired. The socket 7 may be of suitable construction and is adapted to receive and secure a 55 plug 10 of an ordinary electric lighting bulb such as indicated at 11.

A contact ring 12 is mounted on the inner end of the socket or bracket member 7 and is insulated therefrom as indicated at 13. A 60 wire 14 connects the ring with the terminal of the plug 10 and the plug proper forms the return circuit, that is, a grounded single wire circuit is here illustrated, but any type of circuit may be employed, as it does not form 65 any part of the present invention. A yielding brush 15 carried by the back section of the housing delivers the current to the ring and the bulb and the single wire 16, in turn, supplies the brush, an arrangement of this 70 character being more or less essential as the ring and the insulating member rotate in unison with the shaft 6, the socket 7 and the reflector 8, as will hereinafter be described.

The stationary housing is secured in any 75 suitable manner in front of the radiator A. In this instance, a forked bracket 17 is employed, this being, in turn, secured to a forwardly extending arm 18 which is secured to the radiator spout B as indicated at 19. 80 This form of adjustment forms a rigid support for the lamp housing, but any other suitable support may be provided, as long as care is taken that the lamp housing is rigidly supported.

In order that the shaft 6 may be rotated, means must be provided which may be controlled by the operator from the driver's seat. The means illustrated in the present instance is a rod 20. This rod extends 90 through the radiator and is run in under the engine hood. From there it is passed through the instrument board and the inner end is provided with an operating handle 21 which may be positioned within convenient 95 reach of the driver. The outer end of the rod is provided with a universal joint 22. A similar joint 23 is attached to the inner end of the shaft 6 and these joints are connected by means of an angularly disposed 100

shaft 24. A simple easily operated connection is thus provided in conjunction with the shaft 6 whereby the operator or driver may transmit a rotary motion to the shaft.

- 5 In actual practice the parabolic reflector is so positioned with relation to the longitudinal axis of the lamp housing and the shaft 6 as to throw the projected beam to one side of said longitudinal axis or so as to slightly 70 overlap the same. This is best illustrated in the diagrammatic view shown in Figure 2. With the head-light attached to the radiator as shown in Figures 3 and 4 and with the head-light beam projected against a surface 10 forwardly of the car, a circular lighted area will appear as indicated by the circle 27, that is, when the reflector assumes the position shown in Figures 1 and 2. If the shaft 6 is rotated through an angle of 90° to the 75 left, a lighted area such as indicated by the circle 28 will appear. If rotated through an angle of 90° to the right the area indicated by the circle 29 will appear. If rotated 80 180° the uppermost circle 30 will be illustrated, and as the shaft may be rotated to any degree desired, it is obvious that the projected beam may assume any intermediate position desired, for instance, those indicated by the circles 31, 32, 33 and 34. If 85 150 the reflector was stationary the only field of vision obtainable would be the area included within the circle 27.

Not so in the present instance, as the reflector is rotated in unison with the shaft 35 6 and as such permits the projected beam to be swung into any position desired and a complete field of vision may be obtained within the circular area indicated by the large circle 35. A wide range of vision is 40 thus obtained by merely disposing the reflector on an angle and rotating the same about a fixed longitudinal axis.

The ornamental or cover member 9 is circular in outline and concentric with the 45 interior of the housing 2 and has its center of rotation about the shaft 6. The interior of the housing and the mechanism employed is at all times hidden from view by the cover member 9. This materially adds to the ornamental appearance of the headlight and furthermore gives it the appearance of the ordinary stationary parabolic headlight reflectors now in use. The general design of the headlight may thus conform to other 50 headlight equipment employed without interfering with the general construction and mounting of the reflector 8.

By referring to Figure 5, the modified form of the structure is disclosed. In this 55 instance, the reflector 40 is also disposed on an angle, to the shaft 6, but the angle is opposite to that shown in Figure 1. By disposing the reflector on the angle shown in Figure 5 a larger reflecting surface may be 60 obtained and the cover member 9 may be

eliminated. The reflector 40 is an ordinary parabolic type of reflector, but its outer peripheral edge 41 is cut on an angle with relation to the longitudinal axis of the reflector, thereby obtaining an increased reflecting area when comparison is made with the arrangement shown in Figure 1.

While the headlight has been described in conjunction with automobiles, it is obvious that it may be employed on motor boats, 75 ships, and in fact wherever headlights of this character are required. I similarly wish it understood that various changes may be resorted to within the scope of the appended claims and that the materials and finishes of the several parts employed may be such as the manufacturer may decide or varying conditions or uses may demand.

Having thus described my invention what I claim and desire to secure by Letters Patent is:—

1. A head-light of the character described, comprising a substantially cylindrical-shaped housing, a rotatable member journaled in the housing, and a parabolic light reflector secured to said member and disposed within the housing, the longitudinal axis of said reflector being disposed at a predetermined angle to the longitudinal axis of the rotatable member and the housing 90 and maintaining said predetermined angle during rotation of the rotatable member.

2. A head-light of the character described, comprising a substantially cylindrical-shaped housing, a rotatable member journaled in one end of the housing and centrally thereof, a parabolic light reflector secured to said member and disposed within the housing, the longitudinal axis of said reflector being disposed at a predetermined angle to the longitudinal axis of the rotatable member and the housing, and means 100 for rotating the rotatable member and the reflector carried thereby, said reflector maintaining said predetermined angle during rotation of the rotatable member.

3. A head-light of the character described, comprising a substantially cylindrical-shaped housing, a filler plate disposed in the outer end thereof, a parabolic reflector eccentrically positioned with relation to said plate, the longitudinal axis of said reflector being disposed on an angle to the longitudinal axis of the housing, and means for rotating the reflector and the filler plate.

4. A head-light of the character described, comprising a substantially cylindrical-shaped housing, a parabolic reflector mounted within the housing, a rotatable support therefor, said reflector being disposed on an angle with relation to the longitudinal axis of the housing and the rotatable support, a filler plate within the housing and secured to the peripheral edge of the reflector, said filler ring being eccentrically 125 130

positioned with relation to the reflector but concentric with relation to the cylindrical housing.

5. A head-light of the character described, comprising a substantially cylindrical-shaped housing, a parabolic reflector mounted within the housing, a rotatable support therefor, said reflector being disposed on an

angle with relation to the longitudinal axis of the housing and the rotatable support, the peripheral front edge of said reflector being cut on an angle with relation to the longitudinal axis of the reflector so as to present a peripheral surface parallel to the front end of the housing. 10

RUSSELL P. TYLER.
